DESIGN FOR AN ESCUTCHEON PLATE.

Application filed June 12, 1929. Serial No. 31,639. Term of patent 14 years.

To all whom it may concern:

Be it known that I, WALTER R. SCHLAGE, plate,
a citizen of the United States residing at
the city and county of San Francisco, State of
California, have invented a new, original,
and ornamental Design for Escutcheon Plate,
of which the following is a specification,
reference being had to the accompanying
drawings, forming part thereof.

Figure 1 is a front view of the escutcheon
plate,
Fig. 2 is a central vertical longitudinal sec-
tion of the escutcheon plate.

I claim:

The ornamental design for an escutcheon
plate, substantially as shown.

WALTER R. SCHLAGE.
